UNITED STATES PATENT OFFICE.

JEAN CHANAUD, OF NEW YORK, N. Y.

EXERCISING APPARATUS.

1,285,620.

Specification of Letters Patent. Patented Nov. 26, 1918.

Application filed July 23, 1917. Serial No. 182,292. REISSUED.

To all whom it may concern:

Be it known that I, JEAN CHANAUD, a citizen of France, residing at New York city, in the county of New York and State 5 of New York, have invented certain new and useful Improvements in Exercising Apparatus, of which the following is a specification.

This invention relates to exercising apparatus for developing the muscles of the 10 human body.

The main object of the invention is to so construct an apparatus of this character to provide for the rotation of the upper part 15 of the body of the user while the arms are in outstretched position and with the same strain exerted upon each arm.

Another object is to so construct an apparatus of this character as to allow movements of great amplitude and yet use only 20 an ordinary coiled spring.

Another object is to so construct an apparatus of this character in which the cables will be prevented from becoming entangled 25 when not in use.

Still another object of the invention is to provide apparatus of this character, the parts of which are designed to be mounted on supports arranged at diametrically opposite 30 site points to permit the device to be employed for exercises which could not otherwise be accomplished.

With the foregoing and other objects in view, which will appear as the description 35 proceeds, the invention resides in the combination and arrangement of parts and in the details of construction hereinafter described and claimed, it being understood that changes in the precise embodiment of 40 the invention herein disclosed may be made within the scope of what is claimed without departing from the spirit of the invention.

In the accompanying drawings:—

45 Figure 1 is a front elevation of the apparatus,

Fig. 2 is a similar view of the lower end of the cord or cable showing a slightly different form of connection for the hand grip, 50 and

Fig. 3 is a transverse section taken on the line 5—5 of Fig. 4 looking downward.

Fig. 4 is a detail of the limiting member for the cable.

55 In the embodiment illustrated, this im-

proved apparatus constituting the two members A and B is shown mounted upon the opposite walls W of a room, although obviously it may be mounted upon any other suitable supports provided they are disposed directly opposite and are adapted to resist strains to which the apparatus may be subjected.

These members A and B are exactly alike and hence one only will be described in detail. Supporting hooks 1 and 2 are shown mounted in vertically spaced relation on one wall W, the hook 2 being disposed near the floor with its beak turned downward while the hook 1 is spaced some distance above hook 2 with its beak turned upward. A coiled spring 3 of heavy wire and of ample strength to resist the strains to which it may be subjected is shown connected at one end with the beak of hook 2 while the other end thereof is engaged with a hook 4 of a tackle 5 which carries a pulley 6 therein and has an eye 7 disposed opposite the hook 4 and which is designed to receive a hook 8 carried by one end of a cord or cable 14. 70 Another tackle 10 is supported on the hook 1 being engaged therewith by means of an eye and carries at its lower end a small pulley 12 with a larger pulley 13 rotatably mounted therein above the pulley 12 and between it and the eye 11.

80 A flexible cord or cable 14 which may be of any suitable or desired length and which is connected with the hook 8 at one end, passes up over the small pulley 12, then downwardly around pulley 5 and up over pulley 13, and is provided at its free end with a hand grip 15 constructed preferably as shown in Fig. 2 and having a roller 16 85 to permit the device to slip within the hand of the exerciser without injuring it. The member B of the apparatus which is mounted at a point directly opposite member A is, as is shown clearly in Fig. 1 of exactly the same construction, it being obvious that one 90 of the hand grips 15 is designed to be grasped with one hand of the user and the other hand grip with the other hand of the user so that when a pull is exerted by the user on these two grips with the arms in 95 out-stretched position, the same strain will be exerted on both arms owing to the fact that the coiled springs 3 are of uniform strength, thus the user will be permitted to 100 perform a number of exercises which would 105 110

not be possible if the apparatus were constructed as ordinarily and mounted on one wall only of a support.

The hand grips 15 are preferably detachably connected with the free ends of the cables 14 by means of hooks as 17 carried by one end of a heavy wire which is coiled tightly around the end of the cable 14 as is shown clearly in Fig. 3 and by means of 10 which said hook is securely attached to the cable. The end of the hook 17 in Fig. 3 is shown flared outwardly to form a stop to prevent the passage of the cable through pulley 13 if it should be released with the hand 15 grip removed, it being understood that the tension of spring 3 would operate to draw this cable end downward.

In Fig. 4, the hook 17' is shown of slightly different form, the end thereof being shown 20 in alignment with the cable and the stop is formed by winding the opposite end of the wire 18' around the cable 14 and forming a substantially U-shaped loop 19 as is shown clearly in Fig. 5. This loop 19 which projects laterally or radially from the cable 14 will operate to prevent the passage of the cable end through pulley 13 should it be released with the hand grip removed. The cable 14 projects into hook 17' and is 30 rounded, as at 14' so as to close the hook thus preventing accidental removal of the handle or grip 15.

A limiting or stop member 20, shown more clearly in Fig. 6, is secured about cable 14 35 adjacent pulley 13. This member is in the shape of a loop formed from a piece of spring wire and bent in upon itself to form a spring clip 21 which is adapted to grip firmly cable 14. Member 20 is of such size 40 as not to pass between the top bar of the frame supporting pulleys 12 and 13, and pulley 13. This limiting member may be quickly and easily adjusted on cable 14 so as to maintain the cable under tension when 45 grip 15 is released.

By constructing and mounting the cable 14 in the manner above described and as shown by Figs. 1 and 2, when the hand grips 15 are released by the user, the coiled springs 50 13 will draw them upward and hold the cable under tension thereby preventing all

possibility of the stretches thereof becoming entangled.

If desired, the two members A and B may be mounted adjacent each other on the same 55 wall and connected so as to produce a single apparatus, as in Fig. 8 of the drawings. For this purpose, I provide the device shown in Fig. 7. This device is in the form of a double hook having the diverging arms 22 60 and 23 united by a loop 24 adapted to receive a securing hook 25, the upper ends of these arms being maintained in proper spaced relation by a brace rod 26 secured thereto. Arm 22 is provided at its upper 65 end with a spiral loop 27, arm 23 being provided with a similar loop 28. The loops 27 and 28 are adapted to receive the eyes or rings of springs 3 of the members A and B which are mounted adjacent each other and 70 thus operatively connected to form a single apparatus.

From the foregoing description, taken in connection with the accompanying drawings, the advantages of the construction 75 and of the method of operation will be readily apparent to those skilled in the art to which the invention appertains and while I have described the principle of operation of the invention together with the device which 80 I now consider to be the best embodiment thereof, I desire to have it understood that the device shown is merely illustrative and that such changes may be made as are within the scope of the claimed invention. 85

I claim:—

In an exercising apparatus including a block and cable, means for limiting movement of the cable through the block, including a single strand of wire having one terminal coiled about the cable to form closely spaced convolutions and a single larger convolution spaced from the cable to form a stop, the other terminal being formed into a hook for the purpose set forth. 95

In testimony whereof I affix my signature in presence of two witnesses.

JEAN CHANAUD.
